Primary Examiner—Philip S. Hyder**Attorney, Agent, or Firm—Richard L. Miller****[57]****CLAIM**

The ornamental design for a battery holder, as shown and described.

DESCRIPTION

FIG. 1 is a top and perspective view of a battery holder showing my new design;

FIG. 2 is a top plan view thereof;

FIG. 3 is a front elevational view thereof;

FIG. 4 is a left side elevational view thereof the right side elevational view being a mirror image of the view shown;

FIG. 5 is a rear elevational view thereof; and,

FIG. 6 is a bottom plan view thereof.

The broken line showing of the batteries in FIG. 4 is for illustrative purposes only and forms no part of the claimed design.
